UNITED STATES PATENT OFFICE.

ERWIN LAVENS, OF NEW YORK, N. Y., ASSIGNOR TO AARON M. SLOSS,
OF NEW YORK, N. Y.

DESIGN FOR A CABINET.

SPECIFICATION forming part of Design No. 37,314, dated January 31, 1905.

Application filed December 9, 1904. Serial No. 236,234. Term of patent 7 years.

To all whom it may concern:

Be it known that I, ERWIN LAVENS, a citizen of the United States, and a resident of the city of New York, borough of Brooklyn, county of Kings, and State of New York, have invented a new, original, and ornamental Design for Cabinets, of which the annexed drawing is an accurate representation.

The figure of the drawing shows a perspective view of my design for a cabinet.

What I claim is—

The ornamental design for a cabinet, substantially as shown.

ERWIN LAVENS.
